UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,246,545.

Specification of Letters Patent. Patented Nov. 13, 1917.

Application filed August 5, 1916. Serial No. 113,285.

To all whom it may concern:

Be it known that I, HENRY P. CLAUSEN, a citizen of the United States, residing at Mount Vernon, in the county of Westchester 5 and State of New York, have invented certain new and useful Improvements in Telephone-Exchange Systems, of which the following is a full, clear, concise, and exact description.

10 This invention relates to automatic switches for use in telephone exchange systems, and more particularly to non-numerical switches for establishing connection between an incoming line and an idle outgoing trunk.

15 The object of the invention is to provide a switch of this type in which rapid and accurate operation may be obtained.

A feature of the invention is the provision of driving mechanism common to a 20 number of lines and which may be utilized to operate movable contacts individual to said lines, the extent of motion of such contacts being determined by a stop common to the trunks to which such lines have access.

25 A further feature of the invention is the use of line and cut-off relays which control mechanical operations in addition to performing their circuit-controlling functions.

The general operation of a preferred form of the invention is as follows: a wiper rotates over an arcuate bank containing test terminals of a group of trunks until an idle 35 trunk is located. During this hunting movement, a gear wheel is rotated, such gear wheel drawing out a toothed rack arranged to be operated by the plunger of a solenoid. A shaft having a ratchet connection to such 40 gear wheel is provided with a plurality of gear wheels individual to subscribers' lines. When a subscriber initiates a call, his line relay forces a rack bar into engagement with a gear wheel on the common shaft, 45 such rack bar being arranged to move a brush set over trunk terminals upon rotation of said gear wheel. The line relay also completes a circuit for the solenoid, which attracts its plunger, rotating the shaft and 50 causing the brush set individual to the line calling to come to rest on the terminals of the selected trunk. A cut-off relay is then energized to allow the subscribers' rack bar to be drawn from engagement with its associated gear wheel, the bar being held in its 55 elevated position by a pawl controlled by the cut-off relay. The cut-off relay also performs the usual circuit-controlling functions. The test wiper is then again stepped over the master bank contacts in search of 60 the next idle trunk. It is obvious that the extent of motion of the toothed rack operated by the solenoid is determined by the position assumed by the test wiper.

It is thought the invention will best be 65 understood from the following detailed description of the structure and operation of the switch, reference being had to the accompanying drawings.

In the drawings, Figure 1 is a side elevation of the switch structure embodying the present invention; Fig. 2 is a front elevation of the same; Fig. 3 is a detailed view of a lock-out bar; and Fig. 4, illustrates 70 diagrammatically circuits suitable for causing the desired operation of the switch. In the drawings like reference characters indicate like parts.

A shaft 1 is rotatably mounted and carries a plurality of gear wheels 2, there being a gear wheel 2 individual to each calling subscriber. Associated with each gear wheel 2 is a rack bar 3 connected by a link 4 to a brush carriage 5. Rack bar 3 is normally held out of engagement with wheel 2 by the 75 action of a spring 6 through the action of a link 7 pivotally connected at one end to a member 8 in which the rack bar is slidably mounted, and pivotally connected at its other end to the armature 9 of a line relay 80 10. A cut-off relay 11 is arranged to operate a set of contact springs indicated at 12 and a pawl 13 which may be forced into engagement with a series of notches 14 on rack bar 3, against the tension of a spring 85 15 to hold the bar in its elevated position. A sleeve 16 is rotatably mounted on shaft 1 and carries fixedly secured to it a ratchet wheel 17 and a gear wheel 18. A ratchet connection is secured between gear wheel 16 and gear wheel 18 by means of an arm 19 and a dog 20. Gear 18 is engaged by a rack bar 21, which is held in position by a roller 22. At one end of rack bar 21 is secured a magnetic plunger 23 arranged for 90 attraction by a solenoid 24. Wipers 25, 26 secured to ratchet wheel 17 are arranged to rotate with it and to swing over contact sets 27, 28 for a purpose to be hereinafter 95 described. Contact springs 29 individual 100 110

- to each line are arranged to be operated by an insulated knob 30 carried by arms 31 actuated by a common bar 32, which in turn is actuated by a pivoted lever 33 which is moved when plunger 23 approaches the limit of its movement under control of solenoid 24, the extent of movement of plunger 23 and lever 33 being determined by a stop 34. Lever 33 is normally held retracted by a spring 35. Ratchet wheel 17 is arranged to be rotated in a counter-clockwise direction by a pawl 36 actuated by armature 37 of a stepping magnet 38. A locking bar 39 is arranged to be operated by an armature 40 of a locking magnet 41 and is provided with notches 42, as best seen in Fig. 3, with which projections 43 on rack bars 3 may engage when such rack bars are driven into engagement with one of gear wheels 2.
- 20 While the ratchet wheel 17 is being stepped to carry wipers 25 into engagement with contacts of an idle trunk, magnet 41 is energized to move bar 39 to the right so that if a call comes in at this time, the rack 3 individual to such line cannot be forced into engagement with its associated gear wheel 2, since slots 42 are now out of alignment with projections 43.
- Referring now to Fig. 4, the operation of 30 circuits suitable for use with this switch is as follows. Assuming first that the wiper 25 has moved into engagement with the contact 27 of an idle trunk, the rotary motion of ratchet wheel 17 will have actuated gear wheel 18 to draw out rack 21 a distance such that on its return movement a gear wheel 2 will drive a subscriber's brush set carried by his rack 3 into engagement with the terminals of the selected trunk, as previously described. An incoming subscriber's 40 line is represented by conductors 50 and 51. When the subscriber removes his receiver from the hook a circuit is completed from ground, inner upper armature and back contact of cut-off relay 11, line 51, substation apparatus of the called subscriber, line 50, outer upper armature and back contact of cut-off relay 11, right-hand winding of line relay 10, to grounded battery. Relay 10 is 50 energized and attracts its armature, forcing rack 3 into mechanical engagement with a gear wheel 2 and closing at its front contact a circuit from grounded battery, armature and front contact of relay 54, conductor 55, relay 56, conductor 57, armature and back contact of relay 58, conductor 59, left-hand winding of relay 10, contact 60, and armature and front contact of relay 10, to ground. It should be noted at this point that relay 60 54 is energized at all times when there is an available trunk, but will be deenergized when the last trunk relay 61 operates to remove the last of the multiple connections to ground from conductor 62. Contact 60 is closed except when the plunger 23 is fully

attracted by solenoid 24 at which time contact 63 is closed by the operation of common lever 33 and arm 31.

Relay 56 is energized and completes a circuit from grounded battery, armature and front contact of relay 54, conductor 64, winding of solenoid 24, to ground at the armature and front contact of relay 56. The solenoid 24 attracts plunger 23 and withdraws rack bar 21, rotating wheel 18, and the action of dog 20 and arm 19 causes the subscriber's gear wheel 2 to be rotated an equal amount. The rotation of gear wheel 2 causes vertical movement of rack 3, which moves a brush set 65, 66, 67 into engagement with terminals 68, 69, 70 of a selected trunk, the extent of motion of rack 21 being determined by the position assumed by wipers 25 and 26, as previously described. When plunger 24 is fully attracted, contact 60 is opened and contact 63 is closed by the action of arm 31, whereupon a circuit is completed for cut-off relay 11 from grounded battery, winding of relay 11, contact 63, and armature and front contact of relay 10, to ground. Cut-off relay 11 attracts its armatures and at the same time throws pawl 13 into engagement with one of the teeth 14 on the side of rack 3 to maintain the bar in its elevated position. At its upper armatures, cut-off relay 11 opens the circuit of right-hand winding of relay 10, and since the circuit through the left-hand winding was broken by the action of arm 31, relay 10 is deenergized. When relay 10 is deenergized it withdraws rack 3 from engagement with gear wheel 2 by the action of spring 6, as previously described. At its upper armatures and front contacts, relay 11 connects lines 50 and 51 to brushes 65 and 66, and since the brush set 65, 66, 67 has been positioned on terminal set 68, 69, 70, relays 61 and 71 are energized over a circuit from grounded battery, winding of relay 71, terminal 68, brush 65, upper armature and front contact of relay 11, line 50, substation apparatus of the calling subscriber, line 51, inner upper armature and front contact of relay 11, brush 66, terminal 69, winding of relay 61, to ground. While wiper 26 was resting on terminal 28 individual to the trunk selected by the common selecting mechanism, a circuit was closed for slow-release relay 72 from grounded battery, conductor 73, terminal 28 and its wiper 26, resistance 74, to ground. Relay 72 is energized in this circuit and remains energized for a sufficient length of time after wiper 26 has been restored to normal by the action of solenoid 24, to allow the cut-off relay 11 to lock up over a circuit from grounded battery, winding of relay 11, its lower armature and front contact, brush 67, terminal 70, and the armature and front contact of relay 72 to ground. This locking circuit of relay 11 is 130

diverted to ground at the armature of relay 71 as soon as that relay is energized, and the cut-off relay 11 is therefore maintained energized as long as the brush set remains on 5 the terminals of the trunk.

While wiper 25 was resting on a terminal 27 individual to an idle trunk, relay 75 was energized over a circuit from grounded battery, winding of relay 75, wiper 25, terminal 10 27, to ground at the armature and back contact of relay 71. When wiper 25 is restored to its normal position by the action of solenoid 24, relay 75 is deenergized, closing at its armature and back contact a 15 circuit from ground, armature and back contact of slow-release relay 56, armature and back contact of relay 75, stepping magnet 38, slow-release magnet 58, interrupter 76, to grounded battery at the armature and front contact 20 of relay 54. The circuit of magnet 38 is made and broken successively by interrupter 25 76. In response to the operation of magnet 38, ratchet wheel 17 is stepped around, carrying with it wipers 25 and 26 and gear 30 wheel 18, which draws out rack 21. As soon as wiper 25 arrives on a contact 27 associated with an idle trunk, which idle condition would be represented by ground on such terminal 27 due to the deenergized condition 35 of relay 71, a circuit is closed for relay 75 from grounded battery, winding of relay 75, wiper 25, terminal 27, and the armature and back contact of the relay 71 of such idle trunk. Relay 75, at its left-hand armature, 40 opens the previously traced circuit of magnet 38 and allows wiper 25 to come to rest on terminal 27 of such idle trunk. At this time rack bar 21 will have been drawn out a distance such that on its return it will move 45 the brush set of the next calling subscriber a distance sufficient to place such brush set in engagement with the terminal of the selected trunk.

While relay 75 was deenergized, a circuit 50 was closed for locking magnet 41 from grounded battery, winding of magnet 41, to ground at the right-hand armature and back contact of relay 75. Magnet 41 attracts its armature and moves bar 39 to the right to 55 prevent rack 3 being driven into engagement with a gear wheel 2 during the hunting operation of the switch, should a call be initiated during such hunting operation.

When the last available trunk is seized, 60 relay 54 will be deenergized, since the last of its multiple connections to ground will have been removed when relay 61 of such last available trunk is energized. No hunting will take place at this time, since the circuit of stepping magnet 38 is held open at the armature and front contact of relay 54. As soon, however, as a trunk becomes available, relay 54 will again energize due to the deenergization of relay 61 associated with 65 such available trunk, and the circuit of mag-

net 38 will be completed to move the master mechanism into position to select such trunk.

If there should be only one trunk available and the wiper 25 should, for any reason, step past the contact of such trunk, the motion of wiper 25 would continue to the end of the series of contacts, since no ground would be found. On the eleventh step, wiper 26 engages an extra contact 76, whereupon a circuit is closed from grounded battery, armature and contact of relay 54, conductor 55, relay 56, conductor 77, contact 76, wiper 26, resistance 74, to ground. Relay 56 is energized and completes a circuit from grounded battery, armature and contact of relay 54, conductor 64, winding of solenoid 24, to ground at the armature and front contact of relay 56. Rack 21 is then fully retracted by solenoid 24 and hunting again takes place in the manner previously described. 85

After a trunk has been seized and relay 72 has been deenergized, a circuit will be completed for a trunk signal 78 from grounded battery, signal 78, armature and back contact of relay 72, to ground at the armature and front contact of relay 61 which, it will be remembered, was energized when the trunk was seized. A connecting operator at O, one of whose connecting cord plugs is indicated at 79, upon observing the display of signal 78 inserts plug 79 into a jack 80 in which the seized trunk terminates, whereupon relay 72 is energized over a circuit from grounded battery, winding of relay 72, sleeve contact of jack 80, sleeve of plug 79, to ground. From this point the connection may be established in any desired manner. 95

When conversation is completed, the operator at O is informed by the operation of well-known supervisory signals that connection is no longer desired. She thereupon removes plug 79 from jack 80. When the calling subscriber replaced his receiver on the hook relays 61 and 71 were deenergized. The removal of plug 79 from jack 80 allowed relay 72 to deenergize. The locking circuit of cut-off relay 11 is now broken and it deenergizes, thereby withdrawing holding pawl 13 from engagement with one of the teeth 14 on the side of rack 3. Rack bar 3 is then drawn downward to its normal position under the control of a spring 81. The trunk is now in condition to be again selected and 120 the apparatus individual to the calling line is in its normal condition, ready to receive another call. 115

What is claimed is:

1. In a telephone exchange system, incoming and outgoing lines, an automatic switch for interconnecting said lines, movable contacts individual to said incoming lines, driving mechanism therefor common to said incoming lines, a single constantly effective 125

- stop for said driving mechanism, and means for associating a movable contact with said driving mechanism, the extent of motion of said movable contact being limited by said stop. 5
2. In a telephone exchange system, incoming and outgoing lines, an automatic switch for interconnecting said lines, movable contacts individual to said incoming lines, driving mechanism therefor common to said incoming lines, means common to said incoming lines for selecting an idle one of said outgoing lines, said driving mechanism being moved from its normal position a distance dependent upon the position assumed by said selecting means, a single stop for said driving mechanism, and means for associating a movable contact with said driving mechanism, the extent of motion of said movable contact being limited by said stop. 10
3. In a telephone exchange system, incoming and outgoing lines, an automatic switch for interconnecting said lines, movable contacts individual to said incoming lines, driving mechanism therefor common to said incoming lines, means common to said incoming lines for selecting an idle one of said outgoing lines, means for associating a movable contact with said driving mechanism, and means for preventing such association while said selecting means is operating. 15
4. In a telephone exchange system, incoming and outgoing lines, an automatic switch for interconnecting said lines, movable contacts individual to said incoming lines, driving mechanism common to said incoming lines, means common to said incoming lines for selecting an idle one of said outgoing lines, said driving mechanism being moved from its normal position a distance dependent upon the position assumed by said selecting means, means for associating a movable contact with said driving mechanism to connect an incoming line with a selected outgoing line, said selecting means being restored to normal by the operation of said driving mechanism, and means for causing said selecting means to hunt for an idle outgoing line immediately after having been restored to its normal position. 20 50
5. In a telephone exchange system, incoming and outgoing lines, an automatic switch for interconnecting said lines, movable contacts individual to said incoming lines, driving mechanism common to said incoming lines, means common to said incoming lines for selecting an idle one of said outgoing lines, said driving mechanism being moved from its normal position a distance dependent upon the position assumed by said selecting means, means for associating a movable contact with said driving mechanism to connect an incoming line with a selected outgoing line, said selecting means being restored to normal by the operation of said driving mechanism, and means for causing said selecting means to hunt for an idle outgoing line only when one of such lines is available for use. 25 55 60 65
6. In a telephone exchange system, incoming and outgoing lines, an automatic switch for interconnecting said lines, movable contacts individual to said incoming lines, driving mechanism therefor common to said incoming lines, means for associating a movable contact with said driving mechanism to establish connection between an incoming line and an outgoing line, a circuit for controlling said driving mechanism, and means for interrupting the driving circuit of said mechanism when all of said outgoing lines are busy. 70 75 80
- In witness whereof, I hereunto subscribe my name this 4th day of August A. D. 1916.

HENRY P. CLAUSEN.
